TEXTILE MANUFACTURE

Herman T. Gammons, Natick, Mass., assignor to
 Scott & Williams, Incorporated, New York,
 N. Y., a corporation of Massachusetts

Application October 3, 1935, Serial No. 43,350

8 Claims. (Cl. 28—1)

This invention pertains to textile manufacture and relates more particularly to an improved method of making fabric of highly elastic character, for example knitted fabric having inclusions of rubber filaments, threads or yarns. The pending application of Albert E. Page, Serial No. 13,078, filed March 26, 1935, now Patent No. 2,017,444, describes certain of the difficulties commonly experienced in the manufacture of elastic fabrics such as those employed in the making of constrictive apparel, for example corsets, girdles, hosiery and the like,—in particular the trouble experienced in introducing elastic threads during the fabrication of the goods by usual methods of weaving, knitting, etc., on account of the tendency of such elastic thread to stretch excessively when subjected to tension of the order of that applied to the associated inelastic yarns. In said Page application, one desirable mode of procedure in the fabrication of elastic goods is described which, briefly stated, consists in associating with the elastic thread a stretch-limiting factor such as a relatively inelastic strand, and after fabrication of the goods destroying the continuity of such stretch-limiting strand by stretching the goods to such an extent as to rupture the stretch-limiting strand, thereby rendering the latter ineffective and leaving the elastic thread substantially free to stretch in normal manner.

While the method disclosed in the Page application is fundamentally sound and useful for the purpose, the breakage of the stretch-limiting strand by mechanical stress leaves its fragments within the interstices of the goods, and in thin and sheer goods this may be objectionable by reason of the tendency of such fragments of the stretch-limiting strand to work out and expose loose ends at the surface of the fabric, or to impart a mottled appearance to the material. Furthermore, it is requisite that the body of the goods be of such elastic or stretchable character as to permit elongation of the goods as a whole to an extent exceeding the breaking elongation of the stretch-limiting factor and that the body or relatively inelastic yarn be of sufficient strength and so disposed as to withstand, without damage, the stress necessary to break the stretch-limiting strand.

It is the object of the present invention so to employ the underlying principle of the Page invention as to make it applicable to all conditions, and to this end it is proposed to destroy the continuity of the stretch-limiting strand by means other than mere mechanical stress and substantially to eliminate such strand from the material.

Such destruction and elimination of the stretch-limiting strand may be accomplished by chemical or certain physical agencies which attack the stretch-limiting strand with substantially equal vigor at all points in its length and which may, in some embodiments at least, reduce such strand substantially to the condition of dust which is easily beaten, shaken or blown out of the goods.

It is here contemplated that the stretch-limiting factor, as suggested in the Page application, will be a filament, thread, yarn, fine wire or other definitely strand-like element of substantial tensile strength and uniform mass per unit of length, and such as may be produced by any of the usual modes of strand or filament manufacture, such, for example, as spinning, extrusion, drawing or the like, and is to be distinguished from amorphous coatings, sizings, plastic encasements, impregnations or other modes of stiffening, strengthening, or otherwise limiting free contraction or expansion of the elastic thread or yarn, and which have comparatively little tensile strength and which can not be depended upon for uniformity of effect, either in limiting substantial stretch of the rubber strand or in respect to subsequent removal from the goods.

Upon the assumption that such a stretch-limiting strand is to be associated with the elastic yarn or thread so as definitely and reliably to limit the stretch of the latter during fabrication of the goods, the present invention contemplates the employment of a stretch-limiting strand of a material different from that of the body (or relatively inelastic) strands employed in making the fabric,—the materials of the stretch-limiting strand and body yarns being so chosen respectively that they react selectively in a different way when subjected to certain physical or chemical agencies, so that while the body or inelastic yarns are substantially unaffected by said agencies, the stretch-limiting strand is, in a preferred embodiment, substantially eliminated, or at least so changed in its physical characteristics that it wholly loses its destructive character as a stretch-limiting factor.

While as above suggested it is contemplated that either or both physical and chemical agencies may be employed in eliminating the stretch-limiting strand, for example heat, extreme cold, electrolysis or the like, I contemplate the employment of chemical means as the most suitable under average conditions. Thus as a specific example, if the body of the goods is to be of silk, the stretch-limiting strand may be of cotton or other vegetable fiber, and after fabrication of

the goods, the latter may be subjected to a carbonizing process during which the strand of vegetable fiber is attacked by an acid which carbonizes and so weakens it that it may readily be beaten out from the fabric in the form of small particles or dust, although the silk yarns and the included rubber threads will not be substantially affected. Other examples of the invention will be hereinafter more fully described and the mode of procedure illustrated by reference to the accompanying drawing wherein

Fig. 1 is a fragmentary side elevation of a composite thread useful in carrying the improved method into effect, showing one desirable construction and mode of assembling constituent strand elements and illustrating a stretch-limiting factor to be used in the fabrication of goods made from animal fibers or filaments such as wool, hair or silk;

Fig. 2 is a view generally similar to Fig. 1, showing a composite thread constructed in a slightly different way, but with its constituent elements so chosen that the stretch-limiting strand may be employed in the manufacture of goods made from vegetable fiber, such as cotton, jute, etc., or from filaments of vegetable origin, such as those made of regenerated cellulose;

Fig. 3 is a view similar to Fig. 1, but showing a fine metallic wire employed as the stretch-limiting strand;

Fig. 4 is a diagrammatic elevation illustrating apparatus useful in removing the stretch-limiting strand by chemical means after fabrication of the goods;

Fig. 5 is a diagrammatic view illustrating apparatus useful in removing the stretch-limiting strand by electrochemical means after fabrication of the goods;

Fig. 6 is a fragmentary front elevation to large scale, illustrating a rib knitted fabric made of silk yarn and having incorporated therein, as an interlaid strand, a composite thread of the kind shown in Fig. 1,—the parts being shown as they appear at the completion of the knitting operation; and

Fig. 7 is a view similar to Fig. 6, but illustrating the appearance of the goods after the stretch-limiting factor has been removed, and with the goods laterally stretched.

Referring to the drawing the numeral 1 designates a rubber yarn such, for example, as may be made by cutting sheet rubber or by extrusion, and of such cross-sectional area and shape as may be deemed desirable for use in the elastic goods to be made. In accordance with the present invention, a substantially inelastic stretch-limiting strand 2 is disposed parallel to the rubber yarn 1 and in contact with the latter, and is held in association with the strand 1 by any suitable means, for example a helically wrapped strand 3. For certain uses, the rubber yarn is in substantially neutral or unstretched condition when associated with the stretch-limiting strand 2, and desirably, for reasons which will hereinafter more fully appear, the helically wrapped strand 3 should be open wound, but as pointed out in the Page patent above referred to, the rubber strand may be stretched to a greater or lesser predetermined degree preparatory to its association with the stretch limiting factor.

In accordance with the present invention, the stretch-limiting strand is made of a material different from that of the body yarn which is to be employed in fabricating the goods to be made.

Thus, if, for example, it is proposed to make knitted goods from a body yarn or yarns of animal origin, such as silk or wool, the stretch-limiting strand 2 which is associated with the rubber yarn may be of cotton or other vegetable fiber and preferably the helical wrapping strand 3 is of the same material.

The composite thread, comprising the parts 1, 2 and 3, is substantially no more stretchable than any usual textile yarn, being limited in this respect by the substantially straight inelastic strand 2. Having prepared the composite thread, it may now be handled in fabricating the goods in substantially the same way and by the same mechanism, including tensioning devices, as though it were an ordinary textile yarn. Thus in knitting ribbed goods as illustrated in Fig. 6, for example, wherein the body of the fabric consists of a silk yarn or yarns 4, the composite thread of Fig. 1, comprising the elements 1, 2 and 3, is led in through the usual feeding devices and interlaid between the front and rear wales of the knitted material.

Assuming, as above suggested, that the body yarn 4 is of silk and that the strands 2 and 3 are of cotton, these latter strands may now be completely removed by a carbonizing process such as is commonly employed for removing burrs and the like from woolen goods, thus leaving the silk body yarn and the rubber yarn intact. For removal of the vegetable strands 2 and 3 after the goods have been knitted, the goods G (Fig. 4) may first be passed through a bath B of a weak acid, for example, sulphuric or hydrochloric acid, and then caused to enter and pass through a carbonizing chamber C in which the material is exposed to radiant heat from suitable heating coils 5 or the like which concentrate the acid in the interstices of the goods, thereby carbonizing the vegetable strands 2 and 3 and making them very friable. The goods may now be passed through a beater 6 where the material is subjected to a violent beating or brushing and preferably to an air blast whereby the carbonized residue of the cotton strands is entirely removed in the form of dust. The goods may now be washed in any suitable neutralizing and cleansing solution and afterward dried.

When thus freed from the restraining action of the stretch-limiting strand 2, the rubber yarn resumes its normal ability to stretch thus permitting the goods to be stretched laterally, as illustrated, for example, in Fig. 7, the stretched rubber thread 1 then exerting a strong contractive effort such as is desirable in constrictive garments. Since, by the procedure above described, all vestiges of the stretch-limiting factor are removed, the finished goods possess a maximum elasticity and are unblemished by any protruding or included remnants of the stretch-limiting factor. Thus the goods may be made as thin and sheer as desired without danger that its appearance will be marred by the inclusion of the stretch-limiting yarn, and furthermore the goods may be subjected to any desired finishing operation without interference from residue of the stretch-limiting factor.

As a further example of the application of the invention, if it be assumed that the body yarn or yarns to be employed in making the goods is to be of cotton or other vegetable material, then the stretch-limiting strand should be of animal origin such as wool or silk. Thus as illustrated in Fig. 2, the rubber yarn 1 (here shown as enclosed in a close wound helix of cotton yarn 7) has

the stretch-limiting strand 2^a of wool disposed parallel to and in contact with its encasement 7 and held in association with the rubber yarn by means of the open-wound helix 3^a also of wool.

5 This composite thread may now be interlaid between the front and rear wales of a rib knitted fabric knitted from cotton yarn and, after fabrication of the goods, the wool strands 2^a and 3^a may be eliminated by passing the goods through 10 a weak solution of a caustic alkali, for example caustic soda or caustic potash, which selectively attacks the wool but does not injure the cotton or rubber. Subsequently the residue of the wool and the reagent may be removed by passing the 15 goods through appropriate neutralizing and washing baths with subsequent drying and beating if necessary.

As other examples of the selective removal of one textile element, leaving others intact, may 20 be mentioned the use of a silk strand as the stretch-limiting element, used with a body yarn of cotton or wool, the silk being quickly removed by treatment with a boiling 1:1 basic zinc chloride solution, which has little effect on wool or cotton. Likewise, an alkaline solution of copper 25 sulphate and glycerol will remove silk stretch-limiting strands from cotton or wool fabrics. It is further contemplated that the stretch-limiting strand may be made from one of the cellulose 30 derivatives, for example cellulose acetate, which is readily soluble in certain organic solvents, for example acetone, which does not readily dissolve the natural textile yarn such as wool, silk or cotton.

35 A further suggested embodiment of the invention resides in associating with a rubber yarn (for example the yarn 1^b, Fig. 3) a stretch-limiting strand 2^b of very fine metallic wire. Since the tensile strength of metal is so much greater than that of rubber, an extremely fine wire, for 40 example of the order of 0.001 inches in diameter, may be employed, it being obvious that the smaller the wire, provided it affords the requisite stretch-limiting action, the more readily it may be removed after fabrication of the goods. If, for 45 example, the goods to be fabricated are to be of silk, the wire strand 2^b may be held in association with the rubber yarn 1^b by a helically wrapped strand 3^b of silk which will then remain as a 50 permanent part of the goods after fabrication; if the body yarn is to be of cotton then this wrapping strand may be of cotton, etc. When the goods with the composite thread of Fig. 3 included therein have been fabricated, the material M (Fig. 5) may be run through an electrolytic bath E wherein a flexible conductor or conductors A always contact with the metallic inclusions in the goods. Electrical current is supplied to the bath through this contact in such a way that 55 the metal inclusions (the strands 2^b) in the goods constitute the anode, and as the goods slowly move through the electrolyte, the anode is rapidly dissolved out or reduced to a friable oxide. The goods may then be passed through a washing bath W and then through a drying apparatus D, after which they may, if desired, be passed 60 through a beater such as the beater 8 of Fig. 4, where the residue of the metallic inclusions is removed in the form of dust or small particles.

65 70 Even in cases where the stretch-limiting strand is of organic material it may, under some conditions, be desirable to employ electrochemical means rather than purely chemical means alone for destroying the continuity of the stretch-limiting strands and under such conditions appara-

tus generally similar to that illustrated in Fig. 5 may be found desirable.

In the above description reference has been made particularly to the manufacture of elastic knitted goods, but it is to be understood that the invention is not necessarily limited to the manufacture of goods of this particular class but is equally applicable to the manufacture of woven or braided material wherein an elastic strand is to form an element of the fabric. It is further 10 to be understood that while certain specific materials have herein been referred to by way of example, and certain modes of associating the rubber yarn with a stretch-limiting yarn have been described, these particular features have 15 been set forth merely by way of illustration and without intent thereby to limit the scope of the invention.

I claim:

1. That method of making elastic textile fabric comprising a body yarn of relatively inelastic material and an elastic yarn, which comprises as 20 steps preparing a composite thread by so associating a normally elastic yarn with a substantially inelastic stretch-limiting strand that the 25 elastic yarn is unable substantially to elongate in response to applied stress, said inelastic strand being of a material different from that of the body yarn, so manipulating said thread and the body yarn as to cause them to become constituent elements of textile fabric of a predetermined type, thereafter subjecting the fabric to the action of an agency which disintegrates the 30 inelastic stretch-limiting strand but which leaves the body yarn intact, and removing from the fabric the residue of the disintegrated stretch-limiting 35 yarn.

2. That method of making elastic textile fabric comprising a body yarn of relatively inelastic material and an elastic yarn, which comprises as 40 steps preparing a composite thread by so associating a normally elastic yarn with a substantially inelastic stretch-limiting strand that the elastic 45 yarn is unable substantially to elongate in response to applied stress, said inelastic strand being of vegetable origin and the body yarn being of animal origin, so manipulating said thread and the body yarn as to cause them to become constituent elements of a textile fabric of predetermined type, and thereafter subjecting the fabric to the action of an agency which disintegrates the 50 stretch-limiting yarn of vegetable origin while leaving intact the body yarn of animal origin.

3. That method of making elastic textile fabric comprising a body yarn of relatively inelastic material and an elastic yarn, which comprises as 55 steps preparing a composite thread by so associating a normally elastic yarn with a substantially inelastic stretch-limiting strand that the 60 elastic yarn is unable substantially to elongate in response to applied stress, said inelastic strand being of animal origin while the body yarn is of vegetable origin, so manipulating said thread and the body 65 yarn as to cause them to become constituent elements of textile fabric of a predetermined type, thereafter subjecting the fabric to the action of an agency which disintegrates the inelastic stretch-limiting strand of animal origin while leaving the body yarn of vegetable origin intact.

4. That method of making elastic textile fabric comprising a body yarn of relatively inelastic material and an elastic yarn, which comprises 70 75

as steps preparing a composite thread by so associating a normally elastic yarn with a substantially inelastic stretch-limiting strand that the elastic yarn is unable substantially to elongate 5 in response to applied stress, said inelastic strand being of a material different from that of the body yarn, so associating said thread with the body yarn as to cause them to become constituent elements of a textile fabric of a predetermined type, and thereafter subjecting the fabric 10 to the action of a chemical agent which selectively attacks and disintegrates the stretch-limiting yarn throughout substantially its entire length, leaving the body yarn and the rubber yarn 15 intact.

5. That method of making elastic textile fabric comprising a body yarn of relatively inelastic material and an elastic yarn, which comprises as steps preparing a composite thread by so associating a normally elastic yarn with a substantially inelastic stretch-limiting strand that the elastic yarn is unable substantially to elongate in response to applied stress, said inelastic strand being of vegetable origin while the body yarn 25 is of animal origin, so manipulating said thread and body yarn as to cause them to become constituent elements of textile fabric of predetermined type, thereafter subjecting the fabric to the action of a caustic alkali of such strength 30 as to disintegrate the stretch-limiting strand, while leaving the body yarn intact.

6. The method of making elastic textile fabric comprising a body yarn of relatively inelastic material and an elastic yarn, which comprises as steps preparing a composite thread by so associating a normally elastic yarn with a substantially inelastic stretch-limiting strand that the elastic yarn is unable substantially to elongate 35 in response to applied stress, said inelastic strand being of animal origin while the body yarn is of vegetable origin, so manipulating said thread and 40 yarn as to cause them to become constituent ele-

ments of a textile fabric of a predetermined type, thereafter subjecting the fabric to the action of an acid of such strength as to destroy the stretch-limiting strand, while leaving the body yarn intact, and removing from the fabric the residue 5 of the stretch-limiting yarn.

7. That method of making elastic textile fabric comprising a body yarn of relatively inelastic material and an elastic yarn, which comprises as steps preparing a composite thread by so associating a normally elastic yarn with a substantially inelastic stretch-limiting strand that the elastic yarn is unable substantially to elongate in response to applied stress, said inelastic strand being of vegetable origin while the body yarn is 10 of animal origin, so associating said thread and body yarn as to cause them to become constituent elements of a textile fabric of a predetermined type, thereafter subjecting the fabric to the action of a weak acid, heating the fabric thereby 15 to concentrate the acid and carbonize the stretch-limiting strand, and beating the fabric to eliminate the carbonized particles of the disintegrated stretch-limiting strand.

8. That method of making elastic textile fabric comprising a body yarn of relatively inelastic material and an elastic yarn, which comprises as steps preparing a composite thread by so associating a normally elastic yarn with a substantially inelastic stretch-limiting strand that the 20 elastic yarn is unable substantially to elongate in response to applied stress, said inelastic strand being a fine metallic wire while the body yarn is of organic origin, so associating said thread and body yarn as to cause them to become constituent 25 elements of a textile fabric of predetermined type, thereafter subjecting the fabric to electrolytic action in an electrolyte which has no substantial action upon the body yarn but in which the continuity of the metallic wire is destroyed by electrolysis.

HERMAN T. GAMMONS.
